DESIGN FOR AN OPHTHALMIC MOUNTING

Charles O. Cozzens and Edward M. Splaine,
Southbridge, Mass., assignors to American Op-
tical Company, Southbridge, Mass., a voluntary
association of Massachusetts

Application October 12, 1935, Serial No. 58,964

Term of patent 14 years

To all whom it may concern:

Be it known that we, Charles O. Cozzens and Edward M. Splaine, citizens of the United States, residing at Southbridge, in the county of Worcester and State of Massachusetts, have invented a new, original, and ornamental Design for Ophthalmic Mountings, of which the following is a specification, reference being made to the accompanying drawing, forming a part thereof.

Fig. I is an enlarged perspective view of an ophthalmic mounting embodying our design;

Fig. II is an enlarged partial front view of the mounting shown in Fig. I;

Fig. III is an enlarged partial side view of the mounting shown in Fig. I; and

Fig. IV is a partial plan view of the mounting shown in Fig. I.

The characteristic features of applicants' design are shown in full lines.

We claim:

The ornamental design for an ophthalmic mounting, substantially as shown and described.

CHARLES O. COZZENS.
EDWARD M. SPLAINE.
